LAUNDRY APPARATUS

Frank Breckenridge, Mansfield, Ohio, assignor to
Westinghouse Electric & Manufacturing Com-
pany, East Pittsburgh, Pa., a corporation of
Pennsylvania

Application May 13, 1941, Serial No. 393,157

3 Claims. (Cl. 34—45)

This application is a continuation-in-part of my application Serial No. 214,029, filed June 16, 1938.

My invention relates to laundry apparatus and has for an object to provide improved apparatus of this character.

A further object of the invention is to provide improved means for washing and drying fabrics or the like without handling of the fabrics by the operators.

A further object of the invention is to effect, automatically, a series of steps in a washing program including the step of drying the fabrics sufficiently to permit immediate ironing of the same.

It is a further object of the invention to provide improved means for automatically washing fabrics and subsequently removing water therefrom by centrifugal extraction and vaporization.

A still further object of the invention is to provide a novel air heater which may be readily applied to a washer whereby the manufacture of washing apparatus including the drying feature or excluding the same may be economically effected.

These and other objects are effected by my invention as will be apparent from the following description and claims taken in connection with the accompanying drawings forming a part of this application, in which:

Fig. 1 is a vertical sectional view of my improved washing and drying apparatus;

Fig. 2 is a sectional view taken along the line II—II of Fig. 1;

Fig. 3 is a sectional view taken along the line III—III of Fig. 1 and shows the construction of a control detail employed;

Fig. 4 is a diagram showing the electrical connections between the various control devices forming a part of the apparatus;

Fig. 5 is a view of a part of the apparatus shown in Fig. 1 and includes a modified form of air heater; and

Fig. 6 is a diagrammatic view of a modified timer for use in the circuit shown in Fig. 4.

Reference will now be had to Figs. 1 to 4, inclusive, of the drawings wherein I have shown one embodiment of my invention applied to a laundry machine of the domestic type and including a casing structure 10 within which is disposed a washing and drying unit, generally indicated by the numeral 11. The casing 10 may include a frame work 12 formed in any suitable manner, such as, for example, of angle iron, and finishing side and top panels 13 and 14 respec-

tively, secured to the frame work 12. A portion of the front of the cabinet is inclined as shown at 15 and is provided with an access opening 16 formed in the front panel 13. The opening 16 is provided with a closure 17 hinged at 18 and provided with a handle 19. A resilient gasket 21 is preferably carried by the closure 17 and engages the front panel 13 peripherally of the opening 16. As shown in Fig. 1, the top panel 14 is provided with a plurality of air inlet openings 22 for admitting air from the ambient atmosphere to the interior of the casing. One of the side panels 13 is provided with a plurality of air outlet openings 23 for discharging air from within the casing to the ambient atmosphere. Air passed through the openings 22 and 23 is employed for drying the fabrics after washing, further reference to which will be made hereinafter.

20 The washing and drying unit 11 may be supported within the casing 10 in any suitable manner. Preferably, the unit 11 is flexibly mounted within the casing 10 so that vibrations originating in the unit 11 are not transmitted to the casing 10. For the sake of brevity and clearness, the means for mounting the unit 11 within the casing 10 are not shown as they form no part of the present invention. A flexible structure suitable for supporting the unit 11 is disclosed in my Patent No. 2,296,260, granted September 22, 1942, and assigned to the assignee of the present application.

25 The unit 11 includes a fluid-containing tub structure 24, preferably of frusto-conical configuration, and a perforate basket 25 rotatably mounted therein. The basket 25 is also of frusto-conical configuration and closely follows the lines of the tub 24 so that a substantial portion of the liquid contained within the tub structure 24 is disposed within the perforate basket 25. The unit 11 includes a mechanism 26 for driving the basket, which mechanism is carried by the tub structure 24.

30 The tub 24 includes side walls 27 and end walls 28 and 29 at the large and small ends thereof respectively. The axis of the tub structure 24 is inclined as best shown in Fig. 1 and is normal to the plane of the inclined portion of the front wall of the casing. The end wall 28 is provided with an access opening 31 which registers with the access opening 16 of the casing. The space between the tub 24 and the casing 10 adjacent the openings 16 and 31 may be closed by a flexible wall 30 disposed peripherally of said openings. 35 The wall 30 permits relative movement between

the unit 11 and the casing structure 10 while preventing water from entering the interior of the casing 10. Inlet and outlet openings 32 and 33, respectively, are provided in the side wall 24 of the tub structure for the passage of air employed for the drying of the fabrics.

The perforate basket structure 25 is provided with a substantially frusto-conical side wall 34 which is provided with a plurality of perforations 35. Preferably, the entire side wall is perforate. A plurality of vanes 36 are formed within the side wall 34 for agitating the fabrics contained within the basket 25 in the washing fluid as will be described more in detail hereinafter.

The basket 25 is provided with an access opening 37 which is aligned with the access openings 21 and 31. An end wall 38 is provided at the small end of the basket 25 and is dished, as best shown in Fig. 1, to provide a dome within the basket. The basket 25 is supported solely by a shaft 39 that is secured to the basket 25 within the dome 38, which shaft 39 is journaled in a bearing structure 41 carried by the end wall 29 of the tub structure. The shaft 39 is provided with a pulley 42 which is driven by the driving mechanism 26 by means of a belt 43.

The mechanism 26 includes a motor 44 that drives a shaft 45 and a pulley 46 through a two-speed mechanism 47. The pulley 46 is belted to the pulley 42 for rotating the basket 25 at slow speed during the washing cycle and subsequently at high speed for extracting water centrifugally from the fabrics. The two-speed mechanism 47 is of any suitable construction and includes gearing (not shown) which is selectively adjusted to provide relatively high and low speeds of the shaft 45. The two-speed mechanism 47 has not been shown in detail for the sake of brevity, as mechanisms of this kind are well known in the art. An arm 48 is shown for adjusting the mechanism 47 and it will be assumed that the mechanism 47 effects low speed operation of the shaft 45 in the position of the arm 48 shown in full lines and high speed operation of the shaft 45 in the position of the arm 48 shown in broken lines. The arm 48 is biased to its low speed position by a spring 49 and is actuated to its high speed position by an electro-magnet 51 when energized.

Water is admitted to the tub structure 25 in any suitable manner. As shown, in Fig. 1, a conduit 52 is disposed within the casing structure 10 for conveying water to the tub structure 24 and includes a nozzle portion 53 which directs the discharged water toward the center of the basket 25. Hot and cold water from suitable sources are conveyed to the conduit 52 through conduits 54 and 55, the passage of water through the latter being controlled by respective valves 56 and 57. The valves 56 and 57 are preferably electrically operated and are provided with solenoids 58 and 59, respectively. As the construction of solenoid-operated valves is well understood in the art, no further description of their construction and operation is deemed necessary other than to state that they are closed during periods when their respective solenoids are deenergized, and, conversely, are opened when the solenoids are energized.

As shown in Fig. 1, water is discharged from the tub structure 24 through a discharge opening 61 to a suitable drain fitting 62, and, thence from the drain fitting 62 to a point of discharge by means of a pump 63, the outlet of which is connected to

said point of discharge by a flexible conduit 64 which may define a length of rubber hose. Operation of the pump 63 is effected by the motor 44. The inlet of the pump 63 is connected to the drain fitting 62 by a conduit 65 having an electrically-operated valve 66 connected therein and controlling the passage of water to the pump 63. The valve 66 may be operated by a solenoid 67 and is of similar construction to the electrically-operated valves 56 and 57. When the solenoid 67 is deenergized, the valve 66 is closed, and, conversely, when the solenoid 67 is energized, the valve 66 is opened.

The level of the water in the tub structure 24 is controlled by a float switch 71 as best shown in Fig. 3, and controlling energization of the valve solenoids 58 and 59. The float switch 71 includes a vented container 72 which communicates with the interior of the tub structure 24 by means of a conduit 73. Accordingly, the level of the water in the container 72 corresponds to the level of the water in the tub structure 24. The float switch structure 71 includes a suitable switch 74 shown by way of example as an enclosed mercury switch. The switch 74 is actuated by a float 75 that moves upwardly and downwardly on a rod 76 between respective upper and lower shoulders 77 and 78 formed thereon. In the position shown, the float is in its lowermost position in engagement with the stop 78 so that the switch 74 is in its closed position. Accordingly, the solenoids 58 and 59 may be energized and water admitted to the tub 24. When water in the container rises to a predetermined level, the float 75 engages the shoulder 77 and moves the switch 74 to its open position, whereby energization of the solenoids 58 and 59 is prevented.

As will be described more in detail hereinafter, the basket 25 is rotated at slow speed by the shaft 45 to agitate the fabrics in the washing fluid whereby the fabrics are cleaned. Washing fluid is then drained from the tub structure 24 and the basket operated at high speed for centrifugally extracting the washing fluid from the fabrics. Rinse water is then admitted to the tub structure 24 and the fabrics are agitated in the rinse water for a predetermined period of time, during which the detergent in the fabrics is diffused into the rinse water. The rinse water is then discharged from the tub and the fabrics are subjected to a final water extracting operation. After this operation is completed, the fabrics are in a damp condition, and as practiced heretofore, have been removed from the basket for further drying in order to condition the fabrics for ironing. In accordance with my invention, the fabrics are agitated in the basket 25 subsequent to the final extracting operation in the absence of water and are subjected to heated air for vaporizing water from the fabrics whereby they may be removed from the basket and ironed without further drying.

In accordance with my invention, an electrical heater 81 is supported within a casing structure 82, the latter being secured to the exterior of the tub 24 and enclosing the air inlet openings 32 therein, as best shown in Fig. 2. The casing structure 82 is provided with openings 83 for admitting air to the interior thereof, which air is drawn from the ambient atmosphere through the openings 22 formed in the casing structure 10. The air is translated by a fan 84 from the ambient atmosphere in heat exchange relation with the heater 81 and thence through the air inlet openings 32 of the tub structure 24

to the annulus 25a intermediate the tub structure 24 and the basket 25. The heated air is circulated centrifugally within the tub 24 and basket 25 by the vanes 36 of the rotating basket 25. These rotating vanes 36 effect outward movement of the heated air through the perforations 35 and induce a flow of air into the basket 36 through the opening 37. Accordingly, heated air from the annulus 25a circulates through the opening 37 and absorbs moisture from the fabrics which are tumbled within the basket 36. The partly saturated air is returned by centrifugal action through the perforations 35 to the annulus 25a. The fan 84 and the heater 81 provide a continuous supply of dry heated air for circulation through the basket as described. The heated air translated around the annulus 25a absorbs moisture from the air circulated through the basket, as described, and is finally discharged to atmosphere through the outlet openings 33 and 23 in a relatively highly saturated condition.

The fan 84 is driven by an electric motor 85 supported by the casing structure 82 and which is preferably connected in parallel with the heater 81 so that both the heater 81 and the motor 85 are energized simultaneously. The heater 81 may be carried by a frame 86 supported within the casing 82 and preferably, includes a plurality of sections disposed in side-by-side relation in front of the fan 84. (See Fig. 1.)

The air heater 81, the fan motor 85 and the casing 82 are preferably constructed as a unit which is readily attachable to the washing apparatus in any suitable manner as, by screws 82a. It will be noted that the air inlet and outlet openings 32 and 33 are defined by louvers 87, preferably formed integral with the tub structure 24 and so disposed that they prevent water thrown off by the basket 25 during the water-extracting period from being discharged from the tub structure 24.

In accordance with my invention, the driving mechanism 26 for the basket, the heater 81, the fan 84, and the various control instrumentalities for the washing fluid are automatically controlled in order to effect a predetermined washing and drying program without the attention of the operator. The electrical circuits for the aforementioned elements are shown in Fig. 4 and are energized from a suitable source of power indicated by the line conductors L₁ and L₂.

A timing device 91, shown by way of example as an electrically driven drum switch 92, is provided for selectively energizing the various electrical elements of the washer in a predetermined sequence. The timing device 91 which may be secured to the front panel 13 of the casing structure where it is convenient for the operator, includes a relatively small motor 93 of the type usually employed in electric clocks. The motor 93 drives the drum switch 92 through a suitable speed reducer 94, the driven element of which is connected to the drum switch through a slip clutch 95. The drum switch 92 is shown in development and it will be understood that, as it is driven by the motor 93, it is moved in the direction indicated by the arrow. The drum switch 92 may be manually actuated by a knob or handle 96 disposed exteriorly of the casing. The purpose of the slip clutch 95 is to permit manual rotation of the drum switch 92 relative to the speed reducer 94 in order to initiate operation of the apparatus. It will be understood that when the motor 93 is operated, the clutch 95 effects rotation of the drum switch 92.

The drum switch 92 includes a plurality of stationary contact fingers 97 to 102, inclusive, and a plurality of electrically-connected movable contact segments 103 to 110, inclusive. The finger 98 is connected to the line conductor L₁ so that when it is engaged by the segment 103, all of the segments 103 to 110 inclusive are of the same polarity as line conductor L₁. The main motor 44 and the timer motor 93 are connected in parallel between the finger 97 and conductor L₂. The heater 81 and the fan motor 85 are connected in parallel between the finger 102 and conductor L₂. The drain solenoid 67 is connected between the finger 101 and the line conductor L₂. One terminal of the clutch magnet winding 51 is connected to the contact finger 100 and its opposite terminal is connected to the line conductor L₃ through the float switch 74. The water valve solenoids 58 and 59 are connected in parallel, and are connected to the line conductor L₂ through the float switch 74 and to the contact finger 99.

Operation of the washing apparatus is initiated by adjusting the handle 96 (Fig. 4) and drum switch 92 to a position wherein engagement of the segments 103 and 104 with contact fingers 97, 98 and 99 is effected. The duration of the washing period may be varied by the operator and depends upon the amount of movement imparted to the drum switch 92 when starting operation. If the drum switch is adjusted so that the portion of the drum indicated by the line 20M is aligned with the contacts, the washing cycle will continue for a relatively long period, for example, 20 minutes. If the drum is moved manually to a position wherein the portion thereof indicated by the line 5M is aligned with the contacts, the washing cycle will be of relatively short duration, for example, 5 minutes. Intermediate positions may be provided as shown and are indicated at 10M and 15M representing washing periods of 10 and 15 minutes, respectively. A complete cycle of operation will now be described.

Operation

During the inactive periods of the washing apparatus, the control apparatus is in the position shown in Fig. 4. Fabrics to be washed and a detergent, such as, for example, soap, are deposited in the basket 25 through the access opening 16 after which the closure is moved to its closed position. Assuming the condition of the fabrics to be such that a 15 minute washing period is desirable, the drum switch 92 is rotated manually by the handle 96 to a position wherein the drum portion indicated by the line 15M is aligned with the contact fingers. Bridging of the contacts 97 and 98 by the segment 103 energizes the motors 93 and 44, the former operating to effect slow rotation of the drum switch 92. Operation of the motor 44 effects slow speed rotation of the basket 25 as the magnet winding 51 at this time is deenergized and the adjusting arm 48 is in its slow speed position as shown in the drawings.

Engagement of the segment 104 and contact finger 99 energizes the hot and cold water valve solenoids 58 and 59 through the closed float switch 74, whereby water is delivered to the tub structure 24 through the nozzle 53. Delivery of water to the tub continues until the level rises to the location shown by the dot and dash line in Fig. 1, whereupon the float switch 74 is opened and delivery of water to the tub is terminated.

Rotation of the basket 25 at relatively slow

speed is effected so that the fabrics are agitated in the water by the vanes 36. The vanes 36 as they move upwardly out of the water become more and more inclined due to the inclined axis of the basket and direct the fabrics towards the dome 38. The fabrics are elevated by the vanes to an upper region of the basket 25 and are dropped on the dome 38 and slide thereover as they return to the body of washing fluid. Agitation of the fabrics in the fluid and the scrubbing action effected as they slide over the dome 38 effectively removes the soils from the fabrics.

The washing action continues in the example set forth for 15 minutes, at the end of which time the contact segment 108 engages the contact finger 101 whereby the drain valve solenoid 67 is energized and the washing fluid removed from the tub 44 by the pump 63. Engagement of the segment 106 with the finger 100 is effected for energizing the circuit including the magnet winding 51. As the circuit of the magnet winding 51 includes the float switch 74, it will be apparent that it is not completed until the water level in the tub drops sufficiently for effecting closing of the switch 74.

Energization of the magnet winding 51 moves the arm 48 to its dotted position, whereupon high speed operation of the basket 25 is effected. The water remaining in the fabrics is centrifugally extracted therefrom during the high speed operation of the basket and is removed from the tub through the outlet 61 by the pump 63. During spinning of the fabrics, a spray rinse may be effected by the engagement of the segment 105 with the contact finger 99. This operation energizes the water valve solenoids 58 and 59 so that water is delivered to the basket during the spinning of the fabrics. By this operation a certain amount of the detergent in the fluid is diffused in the water which is carried away by the pump 63.

Disengagement of the segments 106 and 108 from their respective fingers 100 and 101 de-energizes the magnet winding 51 and the drain solenoid valve 67. Accordingly, slow speed operation of the basket 25 is initiated and removal of water from the tub terminated. Accordingly, the tub will fill up with clean rinse water until the level of the water has risen sufficiently to open the float switch 74. Agitation of the fabrics in the rinse water is effected for a period of time, or until the segment 109 engages the contact finger 101, whereupon the drain valve 66 is opened by its energized solenoid 67. Accordingly, the rinse water is removed from the tub and high speed operation of the basket is initiated when the segment 107 engages the contact finger 100, as described heretofore. The final extraction of the water from the fabrics is now effected.

Slow speed operation of the basket is initiated when the contact segment 107 becomes disengaged from the finger 100 as described heretofore and the fabrics are tumbled in the basket 25 in the absence of water at this time.

Upon initiating the slow speed operation of the basket, the contact segment 110 engages the contact finger 102, whereupon air from the ambient atmosphere is withdrawn through the air inlet openings 22 and 83 by the fan 84 and is directed in heat exchanging relation with the energized heater 81. The heated air passes through the air inlet opening 32 and contacts the fabrics in the basket, as described heretofore, for vaporizing moisture therefrom. The

air in a highly saturated condition returns to the ambient atmosphere through the air outlet openings 33 and 23 formed in the tub and casing structure, respectively. After a predetermined period of time, the contact segment 110 is disengaged from the finger 102, whereupon energization of the heater 81 and the fan motor 85 is terminated. At the same time, the segment 103 is disengaged from the fingers 97 and 98 for terminating operation of the main driving motor 44 and the timer motor 93. A complete cycle of operation has now been described, and the washing apparatus is in condition for a second operation, the drum switch 92 having been moved to its "off" position as shown in the drawings.

A second embodiment of the invention is shown in Fig. 5 wherein the air heating and translating are disposed within a closure structure 120 for the access opening 16. The washer structure shown in Fig. 5 is of the general type shown in Fig. 1 and portions which are common to each are designated by similar reference characters.

The tub structure 24 in Fig. 5 is provided with a plurality of air outlet openings, a portion of which are shown at 121 and the frame structure 10 is provided with a plurality of outlet openings 122 shown by way of example in the side wall 13. The closure generally shown at 120 includes an outer shell 123 provided with air inlet openings 124 and hinged to the inclined portion of the front wall 15 as shown at 125. A plate 126 is secured to the shell structure 123 and a plurality of air outlet openings 127 are formed in the plate 126 each of which openings 127 is provided with a louver for preventing water splashed in the basket 25 from entering the openings 127.

The frame 128 is carried by the closure 120 and supports a motor 129 and a fan 130 driven thereby. An electrical heater shown at 132 is supported by the frame 128 in any suitable manner. The motor 129 and heater 132 may be energized by conductors 133 which pass through an insulating bushing at 134, formed in the outer shell 123 adjacent the outer hinge 125 thereof. The conductors 133 may be carried within the casing 15 in any suitable manner (not shown).

The apparatus shown in Fig. 5 may be operated automatically in accordance with the washing and drying cycles provided by the timer shown in Figs. 4 and 6. During the water vaporizing period of the cycle, air is translated by the fan 130 from the ambient atmosphere through the openings 124 and thence in heat transfer relation with the heater 132. The heated air passes through the openings 127 directly into the basket structure 25 where it contacts the fabrics being tumbled therein for vaporizing a portion of the water contained in the fabrics. The air in a highly saturated condition passes through the perforations 35 or through the annular space between the end wall 28 of the tub structure 24 and the basket 25. The air is discharged from the tub 24 through the openings 121 and passes to the ambient atmosphere through the openings 122 of the casing structure 10. After the drying cycle is completed, the closure 123 may be swung to its upper position and latched in any suitable manner (not shown), and the fabrics in a dried condition are removed from the basket 25. When the closure 123 is in its open position the plate 126 defines a guard

which prevents the operator from accidentally coming in contact with any of the elements contained within the closure structure 120.

The motor-driven fan 130 in the embodiment shown in Fig. 5 may be omitted if vaporization of moisture from the fabrics is effected with the basket 25 rotating at high speed. In this event, the body of air within the basket is shown centrifugally toward the side walls thereof and passes through the fabrics and perforations in the basket and through the space 140 defined by the end wall 28 of the tub structure and the adjacent end of the basket. Accordingly, flow of air from the ambient atmosphere through the openings 124 to the center of the basket is induced, which air is heated by the heating element 132. The heated, highly saturated air is discharged through the openings 121.

One advantage of the structure shown in Fig. 5 is that two lines of washing apparatus may be readily and economically manufactured, one of the lines including the air heating means and the other excluding the same. This feature is obtainable by providing readily removable closure structures one of which includes the air heating means and another of which merely defines a closure for the access opening, said closures being interchangeable. Accordingly, a washer may be readily adapted for drying the fabrics cleaned thereby, by replacing its cover with a closure structure of the type shown in Fig. 5, it being understood that both types are manufactured with the outlet openings in the casing for the heated air.

This feature is also obtained by the construction of the embodiment shown in Fig. 1 as the heating and air translating means and their casing 82 are constructed as a unit which is readily attachable to the washer construction.

In Fig. 6, I have shown a modified form of timer construction which may be employed for automatically cycling the apparatus described heretofore. With the exception of the addition of a plurality of contact segments 107a, 107b and 107c, the timer, shown in part in Fig. 6, is identical with the timer shown in Fig. 4. Accordingly, the program of washing and drying steps is the same as hereinbefore described with the exception that, during the air drying portion of the cycle, the basket is intermittently rotated at high and low speeds. In this connection, it will be noted that the segments 107a, 107b, and 107c are engageable with the finger 100 and connected in circuit with the clutch solenoid 51 so that when the segments 107a, 107b, or 107c engage the finger 100 energization of the solenoid 51 and high speed operation of the basket are effected.

This intermittent operation of the basket at high and low speeds facilitates drying as the fabrics are redistributed in the basket each time it is operated at high speed. The tendency for the bundle of fabrics to travel in the same path without rearrangement of the fabrics in the bundle during slow speed operation is broken up by the intermittent operation at high speed.

From the foregoing description, it will be apparent that I have provided improved laundry apparatus for washing and drying fabrics, the condition of the fabrics after treatment being such that they may be ironed immediately after

removal from the apparatus. The washing and drying steps are automatically effected without manual attention other than depositing the fabrics and the detergent in the apparatus and initiating operation thereof.

The washing cycle which I have disclosed is shown by way of example and may be varied as desired. It is to be understood that my invention broadly contemplates any washing program wherein drying of the fabrics is included as a step automatically effected in the cycle of operation.

While I have shown my invention in several forms, it will be obvious to those skilled in the art that it is not so limited, but is susceptible to various other modifications and changes without departing from the spirit thereof, and I desire, therefore, that only such limitations shall be placed thereupon as are specifically set forth in the appended claims.

What I claim is:

1. In apparatus for drying fabrics, the combination of a container for the fabrics, means for translating heated air in contact with the fabrics, and means for rotating the container in a single direction at low and high speeds alternately, said rotating means being rendered effective during the period of operation of the air translating means for alternately tumbling the fabrics within the container at relatively low frequency and for rotating the fabrics within the container in a bundle at relatively high frequency.

2. In apparatus for drying fabrics, the combination of a container for the fabrics, means for rotating the container in a single direction at relatively low speed for tumbling the fabrics, means for rotating the container and the enclosed fabrics in the same single direction at relatively high speed, means for translating heated air through the container for abstracting moisture from the fabrics and means for controlling the operation of said rotating means and said air translating means so that they are operated in a predetermined sequence, said controlling means being so constructed and arranged that the rotating means are alternately operated to provide successive periods of low and high speed operation of the container when said air translating means is effective for the circulation of air through the container.

3. In apparatus for drying saturated fabrics or the like, the combination of a container for enclosing the fabrics in a saturated condition, means for rotating the container in a single direction at relatively low and high speeds alternately, means for translating heated air in contact with the fabrics for abstracting moisture therefrom and means adjustable to a plurality of stations for controlling the operation of said rotating means and said air translating means, said control means when adjusted to one of its stations effecting high speed rotation of the container for centrifuging fluid from the fabrics and when adjusted to a plurality of other stations effecting alternate low and high speed rotation of the container and said control means providing for operation of the air translating means when adjusted to said plurality of other stations.
